FIG. 1

FIG. 2

FIG. 2

FIG. 4

FIG. 5

THERMAL VOLTAGE CONTROL FOR A CHRISTMAS TREE LIGHTING SPRING

Heretofore numerous mechanisms and arrangements have been devised to produce an on and off flashing of the lamps of a Christmas tree lighting string. The effect produced by such devices is a sudden and drastic change in lighting intensity that in many instances is distracting and neither pretty nor pleasing. Further, there apparently has been no effort to control the rate of these flashing intervals which frequently are of a duration of less than $\frac{1}{2}$ second. Such spasmodic flashing further detracts from the restful and pleasing effect a lighted Christmas tree is supposed to convey.

It is an object of the present invention to produce a thermoresponsive voltage control for a Christmas tree lighting string that is specifically designed so as not to flash the lamps connected therewith in a conventional manner as by breaking the circuit thereto or by so reducing the voltage to the lamp filaments as to bring them to a cooling point below incandescence, but to slightly and intermittently vary the voltage to the lamps in predetermined increments and thereby to produce in the lamps small changes in lighting intensity and at predetermined spaced intervals to result in a soft, slow, and restful shimmering of the lights heretofore unobtainable with any conventional flasher structure.

While it is understood that the present device may be constructed as an individual plug in unit for use with any lighting string, it is most desirable that it be an integral part of the connector plug or as a fixed assembly connected within the lighting string. Since these lighting strings now vary greatly as to the number and voltages of the lamps used therein as well as different wiring arrangements, series or parallel, it is preferable, for maintaining the operational characteristics desired, that the control be designed specifically for and as a fixed component of the lighting string combination with which it is to be used.

A still further object is to provide a Christmas tree lighting string wherein the connector plug housing the thermal control for shimmering the lamps, further provide for through terminals for connecting to the plug other plug in connectors of other lighting strings in a conventional manner without going through the circuit of the control.

It is a still further object to provide a thermostatic control assembly of the character disclosed which is so constructed as to enable it being tested and adjusted prior to assembly within the lighting string, thereby to more positively assure proper operation of the final product with fewer after assembly rejections.

A further object is to provide for a thermal control as described having identical operating parts, thereby reducing the cost of manufacture and facilitate assembly.

A better understanding of structure and advantage of the device may be had by now referring to the accompanying drawings wherein:

FIG. 1 is an open base view in elevation of the plug in connector of a Christmas tree lighting string showing the arrangement of the thermal control of FIG. 2 arranged therein.

FIG. 2 is a plan view in elevation of the thermal control assembly before mounting within the connector plug of FIGS. 1 and 3.

FIG. 3 is a view in elevation of the connector plug as shown in FIG. 1.

FIG. 4 is a schematic circuit diagram of the invention as wired in combination with a series connected Christmas tree lighting string.

FIG. 5 is a simplified variation of the voltage control of FIG. 2 and wherein the resistor element is of carbon or wire prewound before assembly and mounted in operative relation with the thermoresponsive elements of the device.

Referring now to the drawings and more particularly to FIG. 1, the device of the present invention is shown as including a thermoresponsive voltage control generally designated 5, and as mounted within the connector plug 6 of a series connected lighting string 7 and shown to advantage in FIG. 4.

The control 5 is so constructed as to mount within the connector plug and to the side of the plugs molded center section 8 to which the control is secured as by screws 9 and 10. This center section 8 of the plug is so formed as to rigidly support the extending connector prongs 11 and 12 of the plug and beneath which is secured angular spring terminal members 13 and 14 which serve to contact the connector prongs of a similar connector when the latter is plugged into the device in a conventional manner of connecting one such Christmas tree lighting string with another. It will be here noted that the through circuit through the connector, and formed by the connector prongs and angular terminals, does not require that the current to any attaching connector pass through the mechanism of the voltage control or in any way be affected thereby.

The voltage control of FIG. 2 is shown as including, preferably, a molded plastic mounting plate 15 so elevated at 16 as to provide a mounting flange for the bimetallic strips 17 and 18 secured to the flange as by rivets 19. A terminal wire 20 electrically connects the strips 17 and 18 together. Over these thermal strips are sleeved tubular fiberglass or asbestos insulating members 21 upon which is wound heating resistors 22 and 23. Each of these resistors connect respectively to the thermal strip over which it is wound as at 24 with the other end of the resistor extending to wind about and so connect with terminal members 25 and 26 respectively as shown. These terminal members are so formed as to include angular flange portions 27 and 28 by means of which the control is secured within the plug connector by screws 9 and 10 as previously described. Solder tabs extending from members 28 and 11 provide means for attaching the terminals of the lighting string 7 as at 29 and 30 respectively.

Referring now briefly to the operation of the device thus far described, current, say 115 volts, is applied to the assembly by way of the connector prongs 11 and 12. By reason that the contact pairs 31 and 32 are separated, the heating resistors 22 and 23 are now in series with the lamps of the string and, as shown in FIG. 4, to thereby reduce the voltage to the lamps to its lowest value namely, say 60 volts. Current now passing through these resistors causing them to heat and in turn apply heat through the insulating members 21 to the strips 17 and 18 which, as heated, now begin flexing toward contact closing position. By having slightly different watt heaters or by initially separating one pair of contacts, say 31, more than contacts 32 or by the addition of slightly more insulation 21 between one of the strips and its heater, one pair of contacts, say 31, will close before contacts 32. This closing of contacts 31 shorts out the resistor 22 to increase the voltage to the

lamps by the valve reduced by the resistor to cause a noticeable brightening of the lamps. As the second pair of contacts 33 close, the second resistor 23 is shorted out to cause full brightness of the lamps of the string 7. The shorting of the resistors each affect the other by increasing the voltage therethrough resulting in a slow positive voltage change through the lamps to produce three complete changes in lighting intensity to result in a twinkling and shimmering effect unobtainable with any form of conventional flasher structure.

At no time during the operation of the device is the voltage to the lamps reduced to a valve to cause the filaments of the lamps to cool to a state below incandescence to result in a flashing effect. Preferably, when only one resistor element is used in the circuit, a 30 volt drop to the series is sufficient. When two or more resistors are used, the total voltage drop, desirably, should not exceed 60 volts. A 20 to 25 volt drop for each resistor gives a very satisfactory result, particularly when three or more strings are in simultaneous operation upon a tree.

The device of FIG. 5 is a simplified, easy to construct, variation of the device of FIG. 2 and wherein the resistor 40 is in the form of a carbon rod or a continuous winding of the resistor element 40 upon an insulated wire core or a core of asbestos or fiberglass rod 41. Over the resistor 40 is sleeved, preferably, ceramic tubular beads 42 and 43. The bimetallic strips 44 and 45 are secured as by spot welding at 46 to the terminal plate 47 with the strips being so formed as to partially wrap around the beads as shown to be cemented thereto as at 58. This cement provides for securing the beads against movement along the resistor 40 as well as to assure a good thermal contact between the beads and strips. The cement may be of any type suitable, preferably some form of furnace cement. The strips 44 and 45, as mounted upon the terminal member 47, are secured with the latter to the mounting plate 51 as by rivets 52. Electrical contact is made with the resistor 40 at points 48, 49, and 50 with the thermal strip 44 operative to short out its respective sections of the resistor between points 48 and 49 and with strip 45 operative to short out the resistor section between points 49 and 50. Thermal conductivity of the terminal member 47 between connected strips 44 and 45 is reduced by the cut-out section 53. Mounting and operation of the device of FIG. 5 is substantially as described for FIG. 2, the difference being primarily in the simplicity of construction.

While the devices shown include two resistors and respective thermo-responsive elements to give three distinct lighting intensity effects, it is understood that

one or three or more such assemblies can be used as described without varying from the lamp shimmering concept as provided by the present device. The assembly may be encapsulate within a glass envelope providing the resistance of the heater is greater than that of any one of the lamps of the string and is such as to produce the voltage dropping effect desired and at the damped operating rate desired.

What I therefore claim and desire to cover by letters patent is:

1. A Christmas tree lighting string including in combination a plurality of series connected Christmas tree lamps, a connector plug electrically connected to the terminals of said series for electrically connecting said lighting series to a voltage supply source, a plurality of heating resistors mounted within said plug and connected in series with the lamps of said string the total resistance value of said resistors not reducing the voltage to the lamps of said series by greater than 80% of the voltage of said source, a bimetallic thermal responsive strip respectively associated with each resistor and movable when heated by the latter to respectively short out its associate resistor to produce a brightening of the lamps of the series proportional to the voltage reducing value of the resistor shorted, a thermal conductive mass interposed between said bimetallic strip and its associate resistor to effect thermal lag in the heating and cooling of said strip sufficient to reduce to a predetermined retarded frequency, the resistor shorting and non-shorting operating intervals of said strip.
2. A Christmas tree lighting string including in combination a plurality of series connected Christmas tree lamps, a connector plug electrically connected to the terminals of said series for electrically connecting said lighting series to a voltage supply source, a plurality of heating resistors mounted within said plug and connected in series with the lamps of said string with the total resistance value of said resistors not reducing the voltage from said source to said series by greater than 80 percent, a bimetallic thermal responsive strip respectively associated with each resistor and movable when heated by the latter to respectively short out its associate resistor to produce a brightening of the lamps of the series proportional to the voltage reducing value of the resistor shorted, predetermined volumes of thermal conducting mass respectively interposed in heat communicating relation between each said bimetallic strip and its associate heating resistor to respectively retard, in predetermined differing timed sequence, the thermal response of said strips into and out of their resistor shorting and non-shorting positions.
